UNITED STATES PATENT OFFICE.

JOHN KELLY, OF PEORIA, ILLINOIS.

COMBINED CUT-OFF AND GOVERNOR.

SPECIFICATION forming part of Letters Patent No. 300,267, dated June 10, 1884.

Application filed July 5, 1883. (No model.)

To all whom it may concern:

Be it known that I, JOHN KELLY, of Peoria, in the county of Peoria in the State of Illinois, have invented an Improved Combined Cut-Off and Governor; and I do hereby declare that the following is a full, clear, and exact description thereof, reference being had to the annexed drawings, making a part of this specification, in which like letters of reference refer to like parts, and in which—

Figure 1 represents a longitudinal section of the invention; Fig. 2, a plan view. Fig. 3 is a cross-section. Fig. 4 is a cross-section opposite to Fig. 3; Fig. 5, a diagram of eccentric.

The object of this invention is the construction of means whereby any increase or diminution in the amount of work which an engine is doing alters accordingly the inlet of steam or other motive power into the cylinder. In this invention I have constructed a governing device which not only acts in this way, but also directly upon the slide-valve. In my engine I secure upon the driving-shaft an eccentric having a changeable throw. The driving-pulley is mounted not on the shaft itself, but upon a sleeve rotative thereon. This sleeve has means whereby a partial rotation of itself relative to its shaft shall in one direction increase the throw of the eccentric, and in the other direction shall diminish the throw of the eccentric. The rotation of the shaft is transmitted to the said collar or sleeve, and thereby to the drive-pulley, by means of some strong connection elastically impersable. Said eccentric communicates directly with the slide-valve of the engine. Such a construction would enable the resistance to the engine's drive-pulley to control automatically the supply of steam to the engine's cylinder.

In the drawings, G is the shaft; A, the eccentric; F, the sleeve; W, the drive-pulley; B, the eccentric-strap, having suitable rod connecting it to the slide-valve. The eccentric A has through it a slot, A", in which slides the dog C C', fast upon the shaft G. By moving the center of the eccentric away from the center of the shaft G, its eccentricity and throw is increased, and decreased by an opposite movement. This slot A" and dog C are so set relative to the shaft G that a line drawn through the geometrical center of the eccentric parallel to the sides of the slot A" is be-

tween the center of the shaft and the slide-valve. This offset position of said slot is for the purpose of giving the slide-valve the same lead, however much the eccentric may vary in its throw. I cause the partial rotation of the sleeve F relative to the shaft G to vary the throw of the eccentric A in the following way: At the end of said sleeve, contiguous to the eccentric A, I secure a smaller eccentric, E, but having sufficient throw to be able, by less than an entire revolution of itself relative to the shaft, to move the eccentric A to its greatest eccentricity or to its least. This eccentric E is rotative within the box D, which is fitted between the parallel bars A' A', fast on the eccentric A. As the eccentric E revolves in the box D, which can move easily in the direction parallel to the bars A', but at right angles thereto is resisted, the eccentric A, connected with said bars, is caused to change accordingly its throw.

There are many ways of so connecting the sleeve F and the shaft G together as to allow them to vary, partially, their relative position when under an unequal resistance, but to recover it again as soon as an equilibrium is restored between the applied and the resisting forces. Such ways are, by means of metal springs, confined gases or vapors, and combinations of these. In using a gas or vapor for this purpose, I have designed the construction shown in the drawings.

K is a one-headed cylinder fast upon the shaft G, and having an opening leading thereto through the said shaft from a pipe, L, rotative therein. The tubular piston H fits in said cylinder air-tight, and at its other end is adapted to receive the sleeve F. A slot, H', and pin or feather H" causes them both to rotate together and still have longitudinal motion relative to each other. The slot J' in said piston and a pin, J, projecting from the shaft G, cause the said piston, and therefore its sleeve, to partially rotate upon its shaft whenever the said piston is moved away from the cylinder-head K. Steam or gas being forced in through the pipe L into the cylinder K presses the piston away and toward the drive-pulley W, and causes, through the diagonal slot J', a partial rotation of said wheel and its sleeve.

To prevent rusting of the cylinder and pis-

ton I usually fill said cylinder and the pipe L with oil or other liquid, against which I let the steam press.

When starting this engine, I first turn on the steam-pressure into the pipe L, and cause thereby the piston H to be impressed to its extreme limit. This turns the sleeve F, through the eccentric E, block or box D, and the bars A', the eccentric A is given its greatest throw, 10 and the slide-valve allowed its longest movement. A valve is then turned in the pipe L at a point where the oil or other liquid is not pressed into the cylinder K, and steam turned on into the steam-chest of the engine. As the 15 engine begins its motion and continues to increase its rapidity of revolution, it is ungoverned. Soon, however, as it approaches its maximum of speed, the engineer turns the valve in the pipe L, and allows the backward 20 pressure of the engine's load to affect the drive-pulley and the throw of the changeable eccentric A accordingly. When the said valve was closed, the oil filled completely the cylinder K and prevented the repressing of the drive-pulley; but upon the opening of said valve the elastic force of the steam is allowed to have 25 its effect. Upon any increased resistance to the drive-pulley W it is turned partially relative to its shaft, the eccentricity of the eccentric A increased, and more steam admitted at 30 each stroke to the engine's cylinder. Upon a decrease of resistance to the drive-pulley it is partially advanced by the pressure of the steam acting against the oil or other liquid in the

cylinder K, and the eccentricity of the eccentric A, and the consequent supply of steam to the engine's cylinder, diminished.

What I claim as my invention, and for which I desire Letters Patent, is as follows, to wit:

1. In combination with the driving-shaft of an engine, the eccentric A, having slot A'', the dog C, the sleeve F, having eccentric E, fast thereon, the box D, movable between the bars A', fast on eccentric A, and means whereby the backward turning of said sleeve upon said shaft shall be elastically resisted by said shaft, substantially as and for the purpose specified.

2. The driving-pulley W, shaft G, having tubular end G', cylinder K, having slots J' and H', and the pins J H' therein, in combination with the sleeve F, drive-pulley W thereon, eccentric E, fast at one end of said sleeve, box D, eccentric A, having bars A' and slot A'', and the dog C.

3. The eccentric A, having slot A'', dog or block C, movable in said slot and fast on the shaft G, and the parallel bars A' on said eccentric, in combination with the box D, movable between said bars, and the eccentric E, secured to the end of the sleeve F, whereby the rotation of said sleeve shall shift the eccentric A.

In testimony that I claim the foregoing invention I have hereunto set my hand this 3d day of July, 1883.

JOHN KELLY.
